UNITED STATES PATENT OFFICE.

GUSTAVE L. HERZ, OF NEW YORK, N. Y.

SPARK-PLUG.

1,370,536.

Specification of Letters Patent. Patented Mar. 8, 1921.

Application filed January 17, 1918. Serial No. 212,266.

To all whom it may concern:

Be it known that I, GUSTAVE L. HERZ, a citizen of the United States, and resident of the borough of Manhattan, in the city and State of New York, have invented a new and useful Improvement in Spark-Plugs, of which the following is a specification.

In the manufacture of spark plugs having mica insulators it has been practically impossible to secure an insulator which would not leak or break down under the severe usage to which spark plugs are subjected in use, this leakage especially happening at the inner exposed end of the insulator. This defect came from the inability to properly compress the mica washers at the shouldered inner end of the center electrode and maintain them under proper compression.

The object of my invention is to provide a mica insulator having a stack of mica washers and an independent member composed of a group of mica washers suitably bound together, as, for instance, by an eyelet.

Another object of my invention is more particularly to produce a mica insulator in which the liability of leakage, especially at the inner exposed end of the insulator, is obviated by the introduction of the independent bound group of mica washers at this exposed portion.

A still further object of my invention is to provide means for equalizing the pressure on the mica tube and mica washers by the introduction of means bearing against the outer end of the mica tube.

A practical embodiment of my invention is represented in the accompanying drawings, in which—

Figure 1 represents in side elevation my improved mica insulator mounted on the center electrode of a spark plug.

Fig. 2 is a longitudinal central section through the same, and

Fig. 3 is a longitudinal central section through the eyeleted group of mica washers before being placed in position in the insulator.

The center electrode 1 of the spark plug has a shouldered inner end 2 and a screw threaded outer end 3. The intermediate member of the insulator comprises a mica tube 4 and the body 5 of mica washers. The outer member 6 may be of any suitable insulating material. The inner member

comprises an independent group 7 of mica washers bound together in the present instance by the eyelet 8.

The means for maintaining the insulator in position with the bound group 7 of mica washers tightly engaging the shouldered inner end 2 of the center electrode is shown as a nut 9 engaged with the screw threaded outer end 3 of the electrode.

A metal washer 10 may be located between the outer member 6 and the nut 9.

The outer member 6 may be provided with a centrally arranged recess 11 into which the outer end of the mica tube 4 extends and any means, such, for instance, as a coil spring 12 may be located between the bottom of the recess 11 and the outer end of the mica tube 4 to compensate for differences in compression of the stack of washers and the tube.

The metal eyelet 8 of the group of mica washers snugly fits the center electrode 1 and there are preferably provided annular grooves 13, 14, formed in the bases of the inner and outer flanges 15, 16, so that when the parts are forced into position on the electrode, the mica washers on the eyelet will not be forced outwardly with a tendency to split or break, by the endwise pressure on the eyelet. The flanges 15, 16, overlap the outer and inner faces of the group 7 of mica washers and form, in the present instance, bearings for the mica tube 4 and shouldered end 2 of the electrode. The provision of this independent member at the exposed inner end of the insulator serves to obtain an absolutely non-leakable section at this critical point in the spark plug, viz: that point which is subject to the direct action of the oil and flame when the spark plug is in use.

The inner flange 16 of the eyelet preferably projects beyond the shouldered inner end of the center electrode so as to overlap the outer face of the bound group of washers 7 to a great extent without unduly enlarging the shouldered end of the electrode.

In combining the insulator and center electrode it is understood that the insulator is subjected to endwise pressure against the shouldered inner end of the electrode by any suitable means and the nut 9 is used to maintain the members in their compressed state.

It has been found feasible to make the metal washer 10 and the eyelet 8 of soft metal, such, for instance, as copper.

It is evident that various changes may be resorted to in the form, construction and arrangement of the several parts without departing from the spirit and scope of my invention; hence I do not wish to limit myself strictly to the structure herein shown and described, but

What I claim is:—

1. In a spark plug, a mica insulator including a stack of mica washers, an independent group of mica washers forming an uninterrupted continuation of said stack at the inner exposed end of the insulator, and an eyelet for binding the group together.

2. A mica insulator member composed of a group of mica washers and an eyelet for binding them together, said eyelet having an annular groove at the base of one of its flanges, for the purpose set forth.

3. A mica insulator member composed of a group of mica washers and an eyelet for binding them together, said eyelet having annular grooves at the bases of its flanges, for the purpose set forth.

4. In a spark plug, a mica insulator comprising independent outer, inner and intermediate members, the inner member being composed of a separately bound group of mica washers.

5. In a spark plug, a mica insulator comprising an outer member having a recess, an inner member and an intermediate member comprising a stack of mica washers and a mica tube bearing on the inner member and extending into the recess in the outer member and means bearing against the outer end of said tube.

6. In a spark plug, a center electrode hav-

ing a shouldered inner end, a mica insulator having an independent inner member composed of a separately bound group of mica washers and means maintaining the insulator in position on the electrode with the inner member tightly engaging said shouldered inner end of the electrode. 45

7. In a spark plug, a center electrode having a shouldered inner end, a mica insulator having inner, outer and intermediate members, said intermediate member comprising a stack of mica washers and a mica tube bearing against the inner member and projecting into the outer member, means bearing against the outer end of said tube and means maintaining the insulator in position on the electrode with the inner member tightly engaging said shouldered inner end of the electrode. 50

8. In a spark plug, a center electrode having a shouldered inner end, a mica insulator having an inner member composed of a group of mica washers and an eyelet having flanges overlapping the opposite faces of the group, the inner flange projecting beyond the shouldered inner end of the electrode. 55

9. In a spark plug, a center electrode having a shouldered inner end, a mica insulator having a mica tube and an inner member composed of a group of mica washers and an eyelet having flanges overlapping the opposite faces of the group, said flanges forming bearings respectively for the inner end of the mica tube and the shouldered inner end of the center electrode. 60 70

In testimony, that I claim the foregoing as my invention, I have signed my name, this eleventh day of January, 1918.

GUSTAVE L. HERZ.
